UNITED STATES PATENT OFFICE.

FLETCHER M. CONNER, OF HENRICO COUNTY, VIRGINIA.

CLOTHES-CLAMP FOR BEDS.

SPECIFICATION forming part of Letters Patent No. 319,563, dated June 9, 1885.

Application filed August 28, 1884. (No model.)

To all whom it may concern:

Be it known that I, FLETCHER M. CONNER, a citizen of the United States, residing in Henrico county, Virginia, have invented a 5 certain new and Improved Clothes-Clamp for Beds, of which the following is a full, clear, and exact description.

This invention is a device adapted to hold the bedclothes firmly in the position desired 10 on the bed, so that the occupant—an invalid, child, or restless person—cannot displace or throw off the same or fall out of bed, and also to tuck the bedclothing in.

My invention is composed of the following 15 parts: First, a light metallic rod about one-fourth of an inch in diameter bent into the shape shown by letter *b* in Figure 1 in the accompanying drawings; second, a clamp formed of a small block of wood made as shown by 20 letter *a*; third, an under clamp consisting also of a small block of wood in the shape shown by letter *c*; fourth, a nut of any shape to work easily on the rod upon which a thread is cut, as shown by letter *d*.

25 In the accompanying drawings, in which like parts are designated by similar letters of reference, Fig. 1 is a view of the clamp put together and ready for use. One end of the rod *b* is inserted about an inch and a half into a 30 hole bored the same size as the rod into clamp *a*. It thus goes in tight and will hold. The under clamp, *c*, works loosely on the rod. Fig. 2 is a section of a bed showing the position of the various parts when adjusted on the bed. 35 The bed-clothing is not shown, but it passes

down between the bed and clamp *a* and under the beveled edge of said clamp and up between the same and the side rail and over the side rail.

In applying the clamp the bed-clothing 40 should fall over the side rail of the bed, the clamp *a* being pressed down on the same between the side rail and the bed until wedged in tight, then adjust block *c* and nut *d* as shown. Ordinarily it is not necessary to press block 45 *a* down as far as shown. This device is a new one for the purpose; it will hold the clothing as desired; it will not tear the same or deface the bedstead, there being no contact of the rod with the bedstead; will prevent the occupant from falling out of bed, is easily and quickly adjusted, and upon any kind of bedstead, crib, or cradle, tucks the clothing in, and if adjusted, near the head-board will prevent children throwing their arms out and 55 exposing their shoulders to the cold.

Having described my invention, I claim as new and desire to secure by Letters Patent—

The combination, with the bent rod, screw-threaded and provided with a nut, as described, of the upper clamping-block secured to said rod, and the lower clamping-block working on said rod, as described, and adapted to clamp and hold the bed-clothing down between the side rails of a bed and the bed, 60 substantially as set forth.

FLETCHER M. CONNER.
